CLAIM

The ornamental design for a light box, as shown and described.

DESCRIPTION

FIG. 1 is a top perspective view of the embodiment of a light box which embodies the present design shown in full lines; the items shown in broken lines are depicted for illustrated purposes only and form no part of the claimed design; only one side view of the light box is shown because the each of the side views are identical;

FIG. 2 is a side view of the light box of FIG. 1;

FIG. 3 is a top view of the light box of FIG. 1; and,

FIG. 4 is a bottom view of the light box of FIG. 1.
